UNITED STATES PATENT OFFICE.

LESTER S. KEILHOLTZ, OF DAYTON, OHIO, ASSIGNOR TO DELCO-LIGHT COMPANY, OF DAYTON, OHIO, A CORPORATION OF DELAWARE.

ENGINE.

Application filed October 3, 1923. Serial No. 666,256.

To all whom it may concern:

Be it known that I, LESTER S. KEILHOLTZ, a citizen of the United States of America, residing at Dayton, county of Montgomery, 5 State of Ohio, have invented certain new and useful Improvements in Engines, of which the following is a full, clear, and exact description.

The present invention relates to supply 10 tanks from which a liquid is pumped to a higher level.

It is an object of the invention to maintain substantially constant, as regards the pumping operation, the pressure head due to 15 liquid in the tank, although the level of liquid may vary within certain limits by means of apparatus which is more simple and reliable than heretofore.

The form of invention shown herein constitutes an improvement of apparatus shown in the patent to T. Midgley, No. 1,424,369, issued August 1, 1922, which patent discloses a fuel system for an internal combustion engine including a fuel supply tank having 25 features mentioned in the foregoing. In said patented apparatus it is necessary to provide an airtight joint between the filler opening cover and the tank in order that the apparatus will operate successfully. The 30 present invention requires that the cover of the filler opening be closed but does not require an airtight joint.

Other and further objects and advantages of the present invention will be apparent 35 from the following description, reference being had to the accompanying drawings, wherein a preferred embodiment of one form of the present invention is clearly shown.

40 In the drawings—

Fig. 1 is a fragmentary sectional view of a fuel tank embodying the present invention; and

45 Fig. 2 is a fragmentary plan view of the tank.

In the drawings, 20 is a liquid supply tank having a top wall 21 and a bottom wall 22. The top wall is tapped to receive a bushing 23 which cooperates with a nut 24 to connect 50 pipes 25 and 26 for connecting a pump with the tank near the bottom wall 22 thereof. The pump may be an internal combustion engine which pumps fuel from the tank 20 for combustion in the engine. The top wall 55 21 is apertured and provided with upwardly

extending flange 27 and downwardly extending tubular flange or apron 28. Flanges 27 and 28 constitute a tubular member extending through the top wall 21 of the tank 20 and terminating near the bottom wall 22 to 60 provide a filler passage 29.

The top wall 21 is provided with an upwardly extending boss 32 upon which is pivotally mounted the fuel opening cover 33 having an air vent 34. The cover 33 is 65 latched in position by a bale 35 which is pivoted to ears 35^a provided on wall 21. Cover 33 is provided with an arm 36 which is pivoted to link 37. The top wall 21 is tapped to receive member 40 having a vertical passage 41 in communication with the horizontal passage 42. Passage 42 emerges 70 into passage 43 at a valve seat 44 which is adapted to receive valve 45 connected to link 37. The link 37 projects through nut 46 75 screw threaded upon member 40. The connection between the cover 33 and the valve 45 is such that the valve 45 will be closed upon its seat 44 when the cover 33 closes the filler opening, and the valve 45 is moved 80 away from the seat 44 when cover 33 is tilted back from the opening. In order to allow for variations in manufacture a spring 47 is interposed between the nut 46 and valve 45 to maintain the valve 45 upon its 85 seat 44 when the cover 33 closes the filler opening. The pivotal connections between valve 45 and cover 33 may be made loose enough to permit seating of valve 45 by spring 47. 90

The operation of the tank is as follows:

The cover 33 is swung on its pivot to permit the pouring of fuel through the chamber 29 and to open the valve 45. Fuel entering the chamber 29 will pass into chamber 30 and the air contained within the chamber 30 will be forced by the fuel out of the tank through the passages 41 and 42. After the tank is filled the cover 33 is closed over the flange 27 and the valve 45 will be 100 moved into engagement with seat 44. Assume that the chambers 29 and 30 are filled to the line AA. The engine or other liquid pump being started, liquid will be sucked up through the pipes 24 and 22. The level of 105 the fuel in chamber 29 will quickly drop from the level AA to the level BB at the lower end of said chamber. Level BB may be termed the true hydrostatic level of the tank. It is from this level that the pump 110

suction must lift the liquid to the intake 21. The pressure head in the tank is therefore the distance between the lower end of pipe 25 and level BB.

5 As the pump continues to operate, there will be a tendency for the fuel to drop below the line BB in chamber 29, causing circulation of air bubbles around the bottom edge of flange 28 up through the fuel in 10 chamber 30 to the space above the line AA.

As fuel is pumped from tank 20 the level AA will gradually descend, the fuel removed being displaced by air entering vent 34 and bubbling around the flange 28.

15 It is apparent that the pressure head on pipe line 25, 26 will remain constant for a variation of liquid level in tank 20 between level of the top wall 21 and level BB. Therefore the effect on the pumping apparatus will be constant. This apparatus can be used advantageously in fuel supply systems for internal combustion engines, wherein it is desirable that the fuel mixture proportions should not be affected by variations 25 in fuel level in a supply tank from which the engine pumps fuel direct to the carburetor.

It is to be understood however, that the present invention is not limited to use with 30 engines, as its availability for other uses is apparent.

While the form of mechanism herein shown and described constitutes a preferred embodiment of one form of invention, it is 35 to be understood that other forms might be adopted and various changes and alterations

made in the shape, size, and proportion of the element therein without departing from the spirit and scope of the invention.

What is claimed is as follows:

1. A fuel tank comprising, in combination, 40 a fuel chamber having a vent, a valve, for controlling said vent, means providing a filler passage communicating with the fuel chamber and extending below the top wall thereof, a vented cover for closing said filler passage, and means operated by said cover for opening said vent valve when the cover is moved from its closed to its open position.

2. A fuel tank comprising, in combination, 45 a fuel chamber having a vent, a valve for said vent, a tubular member extending through the top wall of said tank and terminating below said top wall to provide a filler passage, a vented cover for said member, and means connecting the cover and valve for opening the valve when the cover is opened.

3. A fuel tank comprising, in combination, 50 a fuel chamber having a vent, a valve for said vent, means providing a filler passage communicating with the fuel chamber and extending below the top wall thereof, a cover for said filler passage, said passage having communication with the atmosphere 55 when the cover is in closed position, and means operated by said cover for opening said vent valve when the cover is moved from its closed to its open position.

In testimony whereof I hereto affix my 70 signature.

LESTER S. KEILHOLTZ.
